US00D946490S

(12) **United States Design Patent** (10) **Patent No.:** **US D946,490 S**
Li (45) **Date of Patent:** **** Mar. 22, 2022**

(54) **BICYCLE RACK**

(71) Applicant: **SHANGHAI CARTEC INDUSTRIAL & TRADING CO., LTD.**, Shanghai (CN)

(72) Inventor: **Wei Hong Li**, Shanghai (CN)

(73) Assignee: **SHANGHAI CARTEC INDUSTRIAL & TRADING CO., LTD.**, Shanghai (CN)

(**) Term: **15 Years**

(21) Appl. No.: **29/711,394**

(22) Filed: **Oct. 30, 2019**

(51) LOC (13) Cl. **12-16**

(52) U.S. Cl.

USPC **D12/408**

(58) **Field of Classification Search**

USPC D12/115, 406, 407, 408, 412, 414; D6/552

CPC B60R 9/045; B60R 9/048; B60R 9/06; B60R 9/10; B60R 11/00; B62H 3/06; B62H 3/08; B62H 3/12; Y10S 224/924

See application file for complete search history.

(57) **CLAIM**

The ornamental design for a bicycle rack, as shown and described herein.

DESCRIPTION

FIG. 1 is a top right perspective view of a bicycle rack showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures illustrate portions of the bicycle rack that form no part of the claimed design.

1 Claim, 6 Drawing Sheets
